UNITED STATES PATENT OFFICE

KARL FASSNACHT, OF PROVIDENCE, RHODE ISLAND, ASSIGNOR TO SPEIDEL CHAIN CO., OF PROVIDENCE, RHODE ISLAND, A FIRM COMPOSED OF FREDERIC SPEIDEL AND EUGEN SPEIDEL

EXTENSIBLE BRACELET

Application filed October 12, 1929. Serial No. 399,233.

My present invention relates to the jewelry art, and has particular reference to extensible bracelets, watch straps, and the like.

One object of the invention is to provide a novel adjusting mechanism for jewelry of this character.

Another object is to provide a strap formed of two separate parts which may be secured together in adjusted relative position.

10 A further object is to provide a novel lock which grips the edges of an associated strap.

With these and other objects and advantageous features in view, the invention consists of the novel arrangement of parts more fully disclosed in the detailed description following, in conjunction with the accompanying drawings, and more particularly set forth in the appended claims.

In the drawings:

20 Fig. 1 is a top plan view of an improved bracelet;

Fig. 2 is an enlarged bottom plan view showing the adjustable locking members in locking position;

25 Fig. 3 is a side view, partly in section, with the locking members in locking position;

Figs. 4 and 5 are perspective views of the parts forming the clamp member;

30 Figs. 6 and 7 are perspective views showing the elements of the lock member in locking and in releasing position, respectively;

Fig. 8 is a section of the lock member on the line 8-8 of Figure 2; and

Fig. 9 is a section on the line 9-9 of Figure 8.

It has been found desirable in the jewelry art to provide an extensible bracelet or the like with adjustable locking mechanism which will not be conspicuous and which will securely hold the bracelet in the desired position until manually released. I have devised an extensible bracelet formed of two portions which are relatively movable, with a locking mechanism which includes a clamp member 40 on the end of one portion which is engageable

with the other portion, and a lock member on the end of the other portion which grips the edges of the first portion to lock the two portions together, and which is manually releasable when it is desired to change the length of the bracelet; and the following is a detailed description of a specific embodiment of my invention showing the novel locking mechanism applied to a bracelet formed of separate metal links.

Referring to the drawings, 10 designates a bracelet, which is formed of two separate parts 11, 12, which may be termed the upper and the lower portion, and which are secured together by locking mechanism comprising 50 a clamp member 13 and a lock member 14. The clamp member 13 is secured to the end of the lower strap portion 12, and includes a saddle 15 normally mounted to slide over the upper strap portion 11 and a bent lever 65 clamp 16 which has extensions 17 pivotally mounted in suitable openings 18 of the saddle 15, an eye 19 being provided on the clamp 16 for securing the end of the lower strap portion 12 thereto. As shown by Figure 3, a 70 movement of the lower strap portion end away from the upper strap portion will turn the clamp 16 and release the upper strap portion 11, while a movement of the end of strap portion 12 toward the strap portion 11 will 75 turn the clamp 16 to clamp the upper strap portion between the clamp 16 and the saddle 15.

The lock member 14 is secured to the upper strap portion 11 through the usual eye 20 and 80 includes a casing 21, which is preferably formed from sheet metal with two end walls 22, 23, the end wall 22 terminating in the normally downwardly extending bent finger having an upward lateral lock tooth 25. The side wall 23 has a slot 26 therein through which a 85 T-shaped bar 27 extends, as shown in Figure 9, the undersides 28 of the T head 29 being engaged by a compression spring 30 to yielding force the bar into the housing 21. The 90

outwardly extending portion of the bar 27 which extends through the slot 26 is curved downwardly and inwardly to form a bent depending finger with an upward lateral lock tooth 32.

The chain illustrated in Figures 1, 2 and 3 is comprised of metal links 33 hingedly secured together, the pivotal joining leaving aligned openings 34, 35 which are adapted to receive the lock teeth 25 and 32, as hereinafter described.

The operation of the improved locking mechanism is as follows:

Referring to Figures 2 and 8, a manual movement of finger 31 against the compression of spring 30 releases the lock tooth 32 from locking engagement with the slot 35 in the lower portion 12 and permits relative movement of the two strap portions with respect to each other. A movement of the end of portion 12 away from portion 11 now moves the clamp 16 and releases the clamp member from clamping engagement with the upper portion 11, thus permitting adjustment of the bracelet to the desired length. To adjustably lock the two portions together, the clamp member 13 is clamped to the upper portion 11 and the lock member 14 is moved over the lower portion 12 until the two strap portions contact with each other and the lock tooth 26 enters an opening 34. The other finger 31 is now permitted to move inwardly under the pressure of the spring, the lock tooth 32 entering an opening 35 aligned with the opening 34 receiving the lock tooth 26, the tension of the spring 30 now holding the two fingers 24 and 31 and the lock teeth 25 and 32 in locked position.

My improved locking mechanism is not conspicuous, is instantly adjustable to provide a desired length of the extensible bracelet, strap or the like, and securely clamps the two bracelet portions at one point and locks the two portions at another point.

While I have described one specific embodiment as illustrating the principles of my invention, changes both in structure and arrangement may obviously be made without departing from the spirit of the invention as defined in the appended claims.

I claim:

1. An extensible bracelet or the like comprising two portions each formed of pivotally joined links, one of which overlies the other, the sides of contiguous links having spaces therebetween, clamping means on the end of one portion for frictionally engaging the other portion, and locking means on the end of the other portion for releasably extending into the spaces between contiguous links of the first portion to hold the same from slipping therealong.

2. An extensible bracelet or the like comprising two portions each formed of pivotally joined links, one of which overlies the

other, the sides of contiguous links having spaces therebetween, clamping means on the end of one portion for frictionally engaging the other portion, and locking means on the end of the other portion gripping the edges of the first portion and having fingers for releasably extending into the spaces between contiguous links of the first portion.

3. An extensible bracelet or the like comprising two portions each formed of pivotally joined links, one of which overlies the other, the sides of contiguous links having spaces therebetween, clamping means on the end of one portion for frictionally engaging the other portion, and spring pressed locking means on the end of the other portion gripping the opposite edges of the first portion and having fingers for releasably extending into the spaces between contiguous links of the first portion.

4. An extensible bracelet or the like comprising two portions each formed of pivotally joined links, one of which overlies the other, the sides of contiguous links having spaces therebetween, clamping means on the end of one portion for frictionally engaging the other portion, and locking means on the end of the other portion comprising a casing, a finger depending from one end thereof and engaging one edge of the first portion and extending into said spaces, and a movable rod in said casing having a finger depending therefrom for engaging the other edge of the first portion to hold the same between said fingers.

5. An extensible bracelet or the like comprising two portions each formed of pivotally joined links, one of which overlies the other, the sides of contiguous links having spaces therebetween, clamping means on the end of one portion for frictionally engaging the other portion, and locking means on the end of the other portion comprising a casing, a finger depending from one end thereof and engaging one edge of the first portion, and a spring-pressed movable rod in said casing having a finger depending therefrom for engaging the other edge of the first portion to hold the same between said fingers.

6. An extensible bracelet or the like comprising two portions each formed of pivotally joined links, one of which overlies the other, the sides of contiguous links having spaces therebetween, clamping means on the end of one portion for frictionally engaging the other portion, and locking means on the end of the other portion comprising a casing, a finger with a bent end depending therefrom, said bent end extending beneath the first portion and a similar finger movable in said casing and depending from the other side thereof and having its bent end extending beneath the first portion, and a spring for causing said movable finger to move into said casing to grip the edge of the first part.

7. An extensible bracelet or the like comprising two portions each formed of pivotally joined links, one of which overlies the other, the sides of contiguous links having spaces therebetween, clamping means on the end of one portion for frictionally engaging the other portion, locking means on the end of the other portion comprising a casing, and a finger having lips to extend into the spaces between the links to prevent longitudinal movement along the first portion.
